VERTICAL RETORT BENCH

Glenn H. Niles, Ridgewood, N. J., assignor to
Improved Equipment-Russell Engineering Corporation, New York, N. Y., a corporation of Delaware

Application July 3, 1933, Serial No. 678,757

3 Claims. (Cl. 202—253)

This invention relates to apparatus for heat treating solid material, and more particularly to an improved form of vertical carbonizing retort bench adapted for the manufacture of gas and coke from bituminous coal.

A particular object of the invention is to provide an improved type of vertical retort which is adapted for either continuous or intermittent coking of bituminous coal, or for heat treating solid material such as wood, lignite, iron pyrites, oil shale and the like. Another object is to provide coal distilling apparatus of the type referred to having means for varying the operating cycle by adjustment of the liquid seals on the outlets through which the gas and coke products are removed. An important feature of the invention lies in the use of a deep, long and relatively narrow vertical carbonizing retort partitioned lengthwise by a plurality of spaced vertical diaphragms forming carbonizing compartments having separately controlled charging and discharging mechanism whereby the operation of the retort is made flexible and the time required for devolatilizing a charge is materially shortened. Another object is to provide a battery of multi-compartment vertical retorts of the type referred to having secondary air preheating flues and heat interchangers with connections for increasing the heat utilization efficiency of the unit.

With the above and other objects and features in view, the invention consists in the improved carbonizing apparatus hereinafter described and more particularly defined in the claims.

A practical embodiment of my invention is represented in the accompanying drawings, which show a bench of two retorts, it being understood that the number of retorts may be varied to suit different requirements.

Fig. 1 is a view in vertical end elevation of a bench of two retorts, showing one retort in vertical section, taken on the plane 1—1 of Fig. 3.

Fig. 2 is a view in vertical side section, taken on the plane 2—2 of Fig. 1.

Fig. 3 is a horizontal section of the retort bench taken on the plane 3—3 of Fig. 1.

Fig. 4 is a view in vertical side section of the heating flues, taken on the plane 4—4 of Fig. 1.

Fig. 5 is an enlarged detailed view in vertical section, illustrating the charge supporting and dumping elements shown diagrammatically in Fig. 2.

Fig. 6 is a view in vertical section of a modified form of heat interchanger of a type adapted for mounting in the heating flue of the retort setting, as illustrated generally in Fig. 4.

The invention will be hereinafter described with specific reference to its application to the treatment of coal.

As illustrated in Figs. 1 and 2, each vertical retort 10 is tapered and is relatively deep, long and narrow, averaging say 8" in width, with a height of 12' or more, depending upon the character of coke desired. Each retort may have a horizontal length of as much as 7' or 8', and may be divided into two or more vertical compartments 11 by spaced vertical diaphragms 12. The diaphragms 12 extend from the lower end of the retort to a point spaced from the top thereof sufficiently to provide a gas removal header 14 communicably connecting the compartments at the upper end of the retort. At the upper and front end of each retort a gas offtake 15 is provided consisting of a scrubber pipe 17 and hydraulic seal box 18 with connection to the bench gas offtake pipe.

The retorts 10 are mounted in a heating chamber 19 through which heating gases circulate, and the whole structure is supported by girders 20 over a coke quenching tank 22. Each retort 10 is normally separated at its lower end from adjoining retorts in the battery by a division plate 24 extending below the normal level of liquid maintained in tank 22. Liquid is supplied to tank 22 continuously at a rate to replace all evaporation and other losses, through pipe 25. An adjustable overflow pipe 26 in the coke outlet affords the means for varying the depth of sealing liquid in tank 22. Girders 20 are so placed as to form the lower ends of diaphragms 12, but are apertured at 27 to permit intercommunication at all times between the retort compartments.

Between the lower end of each retort and the quenching tank there is mounted a dumping roll 28 adapted to support a charge of fuel in the retort and to discharge coke from the bottom of each retort compartment into the quenching tank. The dumping roll 28 is made up of independently operable sections separately controlling the discharge of coke from each retort compartment 11. Each dumping roll 28 (Fig. 5) consists of 3 roll sections 30, 32 and 34 mounted respectively under each retort compartment 11. The roll 30 which controls discharge of coke from the retort compartment 11 shown on the left hand side of Fig. 2, is loosely journaled on a shaft 36 and is keyed to hollow drive shaft 38, which is journaled in a frame 40 mounted in the front wall of the bench. The roll section 32 which controls the dumping of coke from the central

compartment 11 of Fig. 2, is keyed to shaft 36, which is driven by a gear 42 at a speed which may be varied with respect to the speed at which roll 30 is driven by a gear 44. Another shaft 46, 5 coaxial with shaft 36, has one end journaled in a thrust bearing 48, in which is also journaled an end of shaft 36. Dumping roll 34 is keyed to shaft 46, and shaft 46 is journaled in a frame 50 mounted in the rear wall of the bench. 10 Dumping roll 34 is rotated at a rate controlled by the speed of a gear 51 keyed to shaft 46. The frames 48 and 50, the shafts 36, 38 and 46, and rolls 30, 32 and 34 are removable as units through the front and rear walls of the bench, 15 respectively, without loss of the hydraulic seal on other retorts of the bench.

Coal or other solid material to be heat treated (preferably after crushing to pass a half inch screen) is charged to a retort 16 from an overhead bunker 52 through a gas-tight coal feed valve 54, into an auxiliary coal charging hopper 56. From hopper 56 the supply of coal to each compartment 11 of retort 16 is separately controlled by charging gates 58. The speed of movement of the charge undergoing carbonization in each retort compartment 11 is separately regulated by the rate at which the dumping rolls 30, 32 and 34 remove coke from the bottom of the retort compartments. The speeds at which the 30 respective rolls 36, 32 and 34 are operated is regulated in accordance with the character of coke and gas which it is desired to produce. The coke discharged from each retort compartment falls into the sealing liquid in quenching tank 22, from whence it is discharged by a liquid sealed drag conveyor 60. In passing through the sealing liquid the coke is cooled to a point where its temperature does not substantially exceed 200° F. when finally discharged from the quenching tank by conveyor 60. When discharged at this temperature it can rapidly steam itself dry in the air.

The retorts may be heated with producer gas, oil, pulverized coal, or other available fuel. The 45 heating chamber in which the retorts are mounted comprises a system of horizontal combustion flues 64 which is adapted for the combustion of both liquid and gaseous fuels. A single burner 62 (Fig. 4) may be placed in the lower heating 50 flue 64, or a series of burners may be used at various elevations in the heating flue system on the delayed combustion principle. Air for supporting combustion in the heating flues enters an air heating flue 66 through a register 68 in the front 55 wall of the setting, and becomes preheated by indirect heat exchange with the lower portion of the retort charge while circulating through the air heating flue 66, prior to its entrance into the bottom combustion flue 64. Products of combustion leave the heating chamber at the top 60 through a flue 70 and pass to the stack 72 through a straight pass tubular heat exchanger 74. Before discharging from stack 72 the hot flue gases may be bypassed through a heating coil 76 located in the main coal hopper 52 (Fig. 2). By 65 this means the coal may be thoroughly dried out or heated before it is charged to the retort. Steam may be generated in one section 78 of the heat exchanger 74, while oil fuel for supplying burner 62 may be heated in another section 80 of the heat exchanger.

In case it is desired to use the heat exchanger for supplying hot fuel to a gas or vaporized oil burner 62, the fuel may be vaporized and its heating 70 value modified by bypassing part of the hot

flue gases through one or more bypass tubes 81 into section 83 of the interchanger, and thence around sealed baffle plates 82 into and through a body of oil therein, after which the thus carbureted flue gas is conducted to the burner 62 5 through a pipe connection 83 (Fig. 6).

Intermittent operation of the apparatus involves holding a retort charge at carbonizing temperatures for about four hours, at the end of which time the dumping rolls 28 are slowly rotated to discharge about one half of the depth of charge, or all but say five feet of coke, into the quenching tank. The remainder of the coke is retained in the lower end of the retort as a support for a new coal charge. After dumping the coke a fresh charge of coal is immediately introduced and the discharged coke is removed from the quenching tank by means of the coke conveyor 60. After a retort bench is fully heated, operation of the charging and discharging mechanism may advantageously be made relatively continuous.

Gas produced during the carbonizing operation enters the seal box 18 of the gas offtake through up and down sections 84 and 85 of scrubber pipe 17, in which it is sprayed with light liquor. This scrubbing liquid is collected in the seal box, where it maintains a hydraulic seal between the lower end of the scrubber pipe and the gas outlet connection from box 18. The depth of seal in box 30 18 is regulated by a movable overflow pipe 86 through which the scrubbing liquor drains to a tar seal and separating tank, in which it is settled and repumped to the scrubber pipe. The gas outlet connection from the seal box 18 joins the 35 seal boxes of all the retorts in the bench, and conducts the gas to the foul gas main.

Water in the quenching tank 22 at the foot of the retorts is normally maintained at the level indicated in Fig. 4 to seal each of the retorts independently. By means of the adjustable overflow pipe 26 the level of the sealing liquid in tank 22 may be dropped to unseal the passage around the bottom ends of division plates 24 between all of the retorts surmounting tank 22. This lowering of the liquid seal to permit intercommunication between the retorts may be effected without unsealing the coke outlet conveyor 60. By lowering the depth of liquid seal in tank 22, and simultaneously increasing the depth of seal maintained in the gas offtake sealing box 18 of one retort, sufficient pressure may be placed on one retort of the bench to force the gas generated therein to descend into the quenching tank 22 and pass under plate 24 and up through another retort in 55 the bench, thereby becoming heat-treated during flow through the hot coke charge in the second retort.

Coke in the lower three feet of each retort is cooled by the circulation of air through the 60 air preheating flues 66 which form the side walls of the retort at this level. Water vapor and steam rising from the quenching tank 22 react with the coke in the lower section of the retort to generate blue gas, and this gas, together with 65 the unreacted water vapor carried thereby, have a further direct cooling effect on the lower portion of the retort charge. During the discharge of coke from a retort a relatively large volume of steam is generated, and to escape from the 70 quenching tank this steam must pass up through the down-coming coke in the several retort compartments, cooling it sensibly and endothermically.

The retort compartments 11 may be charged 75

and discharged on alternate cycles. In any case sufficient depth of coke is retained in the bottom of the retort undergoing discharge to effectively prevent any uprush of wet steam into the empty portion of the retort. It has been found that an efficient operation of the retort can be carried out with the production of mixed coal gas and blue gas, by providing sufficient water to generate approximately 130 pounds of steam per ton of coal carbonized. This steam is normally generated in the quenching tank but may be supplemented by steam generated in section 78 of the heat interchanger 74 and admitted as live steam to the quenching tank through an inlet 88.

15 The normal cycle of operation above described may be further varied by introducing carbureting oil through a pipe 99 with coal charged to the retort during the carbonizing cycle. If a lean gas is desired, the carbonizing cycle may 20 be further varied by blasting a controlled amount of air through the retort charge, such air being introduced through an inlet pipe 92 opening into the quenching tank. In place of air, circulation of products of combustion through the retort 25 charge from the flue 70 may be carried out by introducing such gases through an inlet 94 in the quenching tank.

Water is usually used as the sealing liquid in 30 quenching tank 22. However oil may be substituted for water, either exclusively or in a limited amount floating on water in the tank with the consequent production of oil vapor and gas. Coke thus quenched with oil may be returned to 35 the retort; and the retorts are designed so that they may be operated on a complete gasification cycle, in which case the retort charge may be blasted with steam and air until completely consumed.

The invention having been thus described, 40 what is claimed as new is:

1. Apparatus for the distillation of coal and the like, comprising a combination coke quenching and liquid sealed coke removal tank, a plurality of narrow vertical retorts surmounting said 45 quenching tank and having division walls dipping therein and spaced from the bottom thereof, coal charging mechanism overlying each retort in-

cluding gas tight means for supplying charge material at a controlled rate to the retort, a combination charge supporting and coke dumping mechanism mounted at the foot of each retort above the quenching tank and adapted to extract 5 charge material at a controlled rate from the bottom of the retort, conveyer means for removing coke from the bottom of the quenching tank through the liquid seal to the outside of the retort setting, means adapted to maintain an 10 adjustable depth of quenching and sealing liquid in the quenching tank, an individual gas offtake for removing gas from the top of each retort through a hydraulic seal, and individual means for varying depth of hydraulic seal on the gas 15 offtake of each retort.

2. Apparatus of the type defined in claim 1, in which the coke dumping mechanism underlying each retort comprises rolls keyed to individual 20 shafts all journaled in frames adapted for removal as units through the front and rear walls of the retort setting.

3. Apparatus for the distillation of coal and the like, comprising a pair of adjoining vertical retorts having a common dividing wall, spaced 25 vertical diaphragms dividing each retort lengthwise into a plurality of vertical carbonizing compartments, a combination hydraulically sealed coke removal and quenching tank underlying both retorts, the lower ends of said diaphragm 30 and retort dividing wall extending into said tank while spaced from the bottom thereof, an individual gas removal header communicably connecting the tops of all carbonizing compartments 35 of each retort with a hydraulically sealed gas offtake, separate means for adjusting the depth of hydraulic seal in the gas offtake of each retort and the depth of hydraulic seal in the quenching tank, a combination charge supporting 40 and coke dumping mechanism mounted at the foot of each carbonizing compartment above the quenching tank, and mechanism adapted for removing coke from the bottom of the quenching tank without breaking the hydraulic seal 45 maintained therein.
